United States Patent Office

Des. 222,958
Patented Feb. 8, 1972

222,958

SOLID SURFACE FLOOR COVERING OR SIMILAR ARTICLE

Oscar G. Tejeda, Newark, and Harry A. Shortway, Glen
Rock, N.J., assignors to Congoleum Industries, Inc.,
Kearney, N.J.

Filed Mar. 17, 1969, Ser. No. 16,258

Term of patent 14 years

Int. Cl. D6—11

U.S. Cl. D92—4

FIG. 1 is a plan view of a solid surface floor covering embodying our new design showing a regular repeating unit;

FIG. 2 is a sectional view taken along lines 2-2 of FIG. 1;

FIG. 3 is a view of a portion of FIG. 1; and

FIG. 4 is a sectional view taken along lines 4-4 of FIG. 3.

We claim:

The ornamental design for a solid surface floor covering or similar article, substantially as shown and described.
